UNITED STATES PATENT OFFICE

ALVIN G. SHERMAN, OF GROSSE POINTE, MICHIGAN, ASSIGNOR TO DETROIT VAPOR STOVE COMPANY, OF DETROIT, MICHIGAN, A CORPORATION OF MICHIGAN

DESIGN FOR A CABINET RANGE OR SIMILAR ARTICLE

Application filed March 30, 1931. Serial No. 39,299. Term of patent 7 years.

To all whom it may concern:

Be it known that I, ALVIN G. SHERMAN, a citizen of the United States, residing at 216 Lakeland Avenue, Grosse Pointe, in the county of Wayne and State of Michigan, have invented a new, original, and ornamental Design for a Cabinet Range or Similar Article, of which the following is a specification, reference being made to the accompanying drawing, forming part thereof.

Fig. 1 is a perspective view of my cabinet range and showing the drip pan in extended position.

Fig. 2 is a fragmentary view illustrating the drip pan in closed position and combined with the manifold cover to complete the panel.

A dominant feature of the design resides in the panel formed by the front of the burner box and the splitting of this panel so that a portion forms a manifold cover and the other portion a drip pan cover.

I claim:

The ornamental design for a cabinet range or similar article as shown and described.

ALVIN G. SHERMAN.
